Attorney

UNITED STATES PATENT OFFICE.

JOHN HALSALL, OF ELROSE, SASKATCHEWAN, CANADA.

SLEIGH CONSTRUCTION.

Application filed August 24, 1921. Serial No. 494,801.

To all whom it may concern:

Be it known that I, JOHN HALSALL, a citizen of the Dominion of Canada, residing at Elrose, in the county of Moose Jaw 5 and Province of Saskatchewan, have invented certain new and useful Improvements in Sleigh Constructions, of which the following is a specification.

The present invention relates to improvements in sleigh construction, the principal object of the invention being to provide a sleigh adapted to be positioned on a wagon bolster.

With this and other objects in view, the 15 invention consists in the construction, combination and arrangement of parts as will be hereinafter fully described, illustrated in the accompanying drawings and pointed out in the claims hereunto appended.

20 Figure 1 is a side elevation illustrating the embodiment of my present invention.

Fig. 2 is a perspective view of the journal bracket used in my improved sleigh construction.

25 Referring to the drawings, like numerals designate like parts in the various drawings.

The numeral 3 indicates the body or box 30 of a wagon, 4 the bolster. My improved sleigh consists of a runner 5 having a journal bracket 6 substantially mounted on same. Lugs 7 extend downwardly from the bracket and embrace the sides of the runner 5. Lugs 8 extend laterally of the 35 journal bracket 6 and have bolts or lag screws 9 passing through them and embracing the sleigh runner 5. Vertical rods 10, substantially mounted on the sleigh runner 5, extend through the apertures 11 in the lugs 8 and through the apertures 12 positioned in the lugs 13. Brace rod 14 is substantially positioned in the runner 5 as indicated diagrammatically, the vertical members 10 passing through the same 45 and secured by means of nuts 15 positioned on the threaded ends thereof.

The wagon skein or axle is positioned in the aperture 16. Nuts 17, detachably positioned on its other end, prevent displacement of the journal bracket.

It is obvious that I have provided a sleigh construction which may be readily positioned on an ordinary wagon, and while I have illustrated and described the preferred form of construction of my invention, this is capable of variation and modification without departing from the spirit of the invention. I, therefore, do not wish to be limited to the precise details of construction specified, but desire to avail myself of such variations and modifications as come within the scope of the appended claims.

From the foregoing, it is thought that the construction of my invention will be clearly understood and, therefore, a more extended explanation has been omitted.

What I claim as new is:

1. As an improved article of manufacture, a journal bracket having depending 70 lugs upon two opposite sides and lateral lugs upon the other sides, a cylindrical member at the top of said bracket and having an aperture in which is adapted to be received an axle skein, and lugs on opposite 75 sides of said cylindrical member apertured to receive vertical rods.

2. In combination, runner members, a journal bracket on each member, each bracket having lateral side lugs resting on 80 said members, and end lugs depending from the bracket, and embracing the said members, means securing said side and end lugs to said members, a cylindrical member at the top of each bracket, a wagon skein 85 in the said cylindrical members, lateral lugs on said cylindrical members, rods passed through said lugs and through said lateral lugs at the bases of said brackets and into the runner members, and braces 90 secured by said rods on the cylindrical members and having their ends secured to the runner members.

In testimony whereof, I affix my signature in the presence of two witnesses.

JOHN HALSALL.

Witnesses:

B. LESTER,
H. TALBOT.
